SPORT TROUSERS

Lorena G. Bedient, Marshall, and Julia E. Mewes,
Spokane, Wash., assignors of one-third to Ruth W.
Dobson, Spokane, Wash.

Filed Feb. 24, 1961, Ser. No. 64,053

Term of patent 14 years

(Cl. D3—17)

Fig. 1

Fig. 2

FIG. 1 is a front view of a pair of sport trousers showing our new design;

FIG. 2 is a rear view thereof on a reduced scale; and

FIG. 3 is a side view thereof.

The essential features of our design reside in the portions shown in full lines on the drawings.

We claim:

The ornamental design for sport trousers, as shown and described.
